CATHETER TRAY

Herbert E. Turner, 1129 Carr, Memphis, Tenn.

Filed May 1, 1964, Ser. No. 79,766

Term of patent 14 years

(Cl. D83—1)

FIG. 1

FIG. 2

FIG. 3

FIG. 4

FIG. 1 is a perspective view of a catheter tray showing my new design;

FIG. 2 is a top plan view thereof, taken on a reduced scale;

FIG. 3 is a front elevation thereof; and

FIG. 4 is a side elevation thereof.

I claim:

The ornamental design for a catheter tray, as shown.
